PULLING DIE

Abraham Solosko, Chicago, Ill.

Application May 1, 1936, Serial No. 77,352

5 Claims. (Cl. 223—25)

This invention relates to pulling dies for hats. In machines of this character, there is usually provided a stand or base on which a form is mounted to receive a hat. This form, which constitutes the die, is utilized in stretching or shaping hats and pressing the same.

One form of the invention is shown as embodied in a device of this character having a stand on which there is removably and adjustably mounted a hollow crown form.

One feature of the invention comprises the embodiment, in a structure of the class described, of means whereby the hat form may be raised from the stand and a ring inserted between the form and the stand for the purposes of increasing the height of the crown part of the hat.

The invention further comprises certain novel features of construction whereby the hat crown form is readily raised or clamped in position, as desired.

Other features and advantages of the invention will appear more clearly from the following description, reference being had to the accompanying drawings wherein a preferred form of the invention is shown.

In the drawings—

Fig. 1 is a view in side elevation of a device embodying the invention;

Fig. 2 is a plan sectional view on the line 2—2 of Fig. 1;

Fig. 3 is a sectional view on the line 3—3 of Fig. 2;

Fig. 4 is a sectional view on the line 3—3 of Fig. 2 showing a spacing ring interposed between the hat crown form and the stand;

Fig. 5 is a fragmentary view of a part of the mechanism shown in Figs. 3 and 4, illustrating a changed position; and

Fig. 6 is a fragmentary sectional view on the line 6—6 of Fig. 4.

Referring now to the drawings, the invention is shown as embodied in a device of the character described which comprises a stand or base 10. The base 10 has a plurality of legs 11 which are formed as an integral part of the base 10. This base also has an outwardly flared annular surface 12 at its top which is adapted to receive the brim of a hat when the hat is drawn down upon a crown form 13 that is supported by the base 10. The base 10 and the form 13 may desirably be made of metal castings and are polished to give a smooth exterior surface.

The form 13 is positioned on the top of the base 10 by means of a plurality of locating projections 14, 15, 16, and 17 which are formed upon

a flat top surface 18 provided on the base 10. The form 13 has a series of recesses adapted to receive the projections 14, 15, 16, and 17 to insure proper positioning between the parts.

Means are provided for clamping the form 13 down in position upon the top surface 18 of the base 10. This means comprises a depending bar 19 which is swivelled in the hollow interior of the form 13 by means of a bearing member 20 secured to the form by screws 21. The bar 19 has a rounded head 22 which is held by the bearing member 20. The bar 19 also has ratchet teeth 23 thereon which are adapted to engage with a tooth 24 on a pawl member 25. The pawl member 25 is supported by means of a pivot pin 26 which is passed through a pair of ears 27 and 28 that project upwardly from a pair of supporting brackets 29 and 30 that are formed integral with the base 10. The pawl member 25 is bifurcated to provide a pair of arms 31 and 32 which arms embrace the bar 19 and which carry a roller 33 adapted to bear against the back side of the bar 19 so as to urge the ratchet teeth 23 against the tooth 24. The roller is mounted upon a pin 34 similar to pin 26. Cotter pins 35 are used to secure the pins 26 and 34 in position.

The pawl 25 is actuated by a mechanism which comprises a link 36 that is bifurcated at its upper end and secured to the pawl 25 by means of a pin 37 which is secured in place by a cotter pin 38. The link 36 is provided with a plurality of openings 39 whereby it may be adjustably connected to one end 40 of an adjusting lever 41. The lever 41 is secured to the base 10 by means of a pair of lugs 42 that are cast thereon and a pin 43 as will be readily understood. The actuating lever 41 has a handle portion 44 projecting out from the base 10. This portion is adapted to engage a set screw 45 that is screw threaded into a lug 46 that extends horizontally from the base 10.

It is believed to be evident from an inspection of Fig. 2, 3 and 5 that lifting up of the handle portion 44 of the lever 41 will move the tooth 24 of the pawl 25 up along the teeth 23 of the bar 19, and that, by moving the handle portion 44 of the lever 41 down, as for example by operating the set screw 45, the tooth 24 may be caused to draw the bar 19 downwardly so as to clamp the crown form 13 tightly in position on top of the base 10.

In order to raise the form 13 higher when it is desired to increase the height of the hat crown, the form is loosened by releasing the set screw 45.

45 so that the handle 44 can be raised to release the tooth 24 in the manner shown in Fig. 5. The entire form 13 and its bar 19 can then be freely removed from the base 10. The crown 5 height is built up by placing on the base 10 a ring 47 which is recessed on its lower surface to receive the guide projections 14, 15, 16, and 17 in the manner shown in Figs. 4 and 6. On its upper surface, this ring is provided with corresponding projections such as 48 that are vertically aligned with the recess that receive the projections 14, 15, 16, and 17. The form 13 is set in place upon the ring 47, and the entire assembly is clamped together by manipulation 15 of the pawl 25 as will be readily understood. Any desired number of the rings 47 of different thickness may be used. If it is desirable, more than one ring 47 may be interposed between the crown form 13 and the base 10.

20 While certain embodiments of the invention have been shown and described, it is to be understood that it is capable of many modifications. Changes, therefore, in the construction and arrangement may be made without departing from 25 the spirit and scope of the invention as disclosed in the appended claims in which it is the intention to claim all novelty inherent in the invention as broadly as possible in view of the prior art.

Having thus described the invention, what I 30 claim as new and desire to secure by Letters Patent is:

1. A device of the character described comprising a base, a crown form adapted to rest thereon to provide a die on which a hat may be shaped, and means for clamping said crown form in position on the base comprising aligning means 35 on the base and the crown form, a depending bar inside said crown form, ratchet teeth on said bar, an adjustable pawl in the base adapted to engage said ratchet teeth, means for moving said pawl to draw the bar downwardly whereby to press the crown form against the base.

2. A device of the character described comprising a base, a crown form adapted to rest thereon to provide a die on which a hat may be shaped, and means for clamping said crown form in position on the base comprising aligning means 5 on the base and the crown form, a depending bar inside said crown form, ratchet teeth on said bar, an adjustable pawl in the base adapted to engage said ratchet teeth, means for moving said pawl to draw the bar downwardly whereby to 10 press the crown form against the base, and a spacing device interposed between the crown form and the base and having vertically aligned positioning means thereon engaging said aligning means to position the crown form on the base. 15

3. A pulling die of the character described comprising an annular base, a hollow crown form cooperating with said base to provide a die on which a hat may be shaped, said crown form being vertically adjustable upon the base, a spacing ring interposed between the crown form and the base, and means to press the crown form toward the base. 20

4. A device of the character described comprising a base, a crown form supported thereon to provide a die on which a hat may be shaped, and means for clamping said crown form on the base comprising a securing device suspended inside said crown form, a crown form tightening means in said base engaging said device for 25 pulling it downward, and manually operable means carried by said base for actuating said tightening means.

5. A pulling die of the character described comprising a base having a brim forming surface 35 and having an annular crown form supporting portion, a hollow crown form having a lower rim supported by said portion, and means to clamp said crown form to said base comprising cooperating clamping members in said crown 40 and base respectively.

ABRAHAM SOLOSKO.
